BURNER OF THE PROJECTED FLAME TYPE

James William Pennington, Chicago, Ill., assignor
to Inland Steel Company, Chicago, Ill., a cor-
poration of Delaware

Application August 23, 1950, Serial No. 181,022

24 Claims. (Cl. 158—11)

1

This invention relates to a burner, which is adapted particularly for use under conditions requiring projection of a flame of high intensity. Such burners are useful, for example, in the melting of metal in furnaces of the open hearth type, although not necessarily limited to such application.

An object of the invention is to improve the efficiency of burners of the general character herein disclosed, and to obtain maximum combustion of the fuel with higher flame temperatures.

Another object is to produce a burner of the character stated, which is self-cleaning, and capable of operating throughout extended periods of time without servicing.

Another object is to so construct the burner as to greatly extend its useful life, while at the same time reducing the cost of manufacture and the cost of maintenance thereof.

The foregoing and other objects are attained by the means described herein and illustrated upon the accompanying drawings, in which:

Fig. 1 is a cross-sectional view showing part of an open hearth furnace, with the improved burner of the invention being illustrated in side elevation.

Fig. 2 is an enlarged cross-sectional view taken on line 2—2 of Fig. 1.

Fig. 3 is a side elevational view, partly broken away, showing a forward tube support member incorporated in the burner nose.

Fig. 4 is a side elevational view, partly broken away, showing a part of the tube support member.

Fig. 5 is a vertical section taken at the rear portion of the burner, showing the structure on an enlarged scale.

Fig. 6 is a cross-sectional view taken on line 6—6 of Fig. 5.

Fig. 7 is a vertical section, at twice the scale of Fig. 5, showing the forward or nose end of the burner.

Fig. 8 is a fragmentary end elevational view of the nose end of the burner illustrated by Fig. 7.

Fig. 9 is a front view of a modified form of burner.

Fig. 10 is a cross-sectional view taken on line 10—10 of Fig. 9.

In Fig. 1 of the drawings, a burner 10 embodying the invention is shown mounted in place on a furnace such as an open hearth, for example. The burner extends through a port 12 in the furnace wall, and may be supported upon

2

trunnions 13 journaled in bearing brackets 14, one at each side of the burner. The brackets may be secured to a transverse beam 15 supported by the furnace wall or otherwise. The burner may be swung or rocked upon the trunnions 13, as by means of a screw 16 and handwheel 17, for directing the flame of the burner to a desired angle upon the melt which rests upon the hearth forwardly of the burner.

10 The nose end 18 of the burner is adapted to deliver into the furnace, a combustible atomized mixture of oil, gas, oxygen and steam, or various combinations thereof. The gas used may be coke oven gas, illuminating gas, or the equivalent, and in some instances various grades or types of tar, pitch, or the like, is substituted for the oil or mixed therewith to form a proper viscous fuel.

15 Referring to Figs. 1 and 6, the supply pipe for viscous fuel or oil is indicated at 19; the supply pipe for gas or gaseous fuel is shown at 20; the supply pipe for oxygen or its equivalent is at 21; steam pipes are shown at 22, 23, 24 and 25; and pipes for a cooling fluid, such as water, are indicated by the characters 26, 27, and 28. Pipe 28 is furnished with a cock 29 and a cap 30, which constitute a blow-off arrangement for clearing the cooling system of dirt, sediment, and any foreign matter that might accumulate therein. Cooling fluid normally may enter the pipe 27 which conveys it to the forward end of the encircling water jacket 31 of the burner, whereas pipe 26 exhausts the cooling fluid from the jacket. The flow of cooling fluid through the jacket preferably is continuous.

30 35 It should be understood that the various pipes mentioned in the paragraph next above are usually connected with sources of supply which can be controlled by means of valves or otherwise, and due to the fact that the burner is rockable upon its trunnions 13, the connections are necessarily flexible. Flexible hoses or swivel couplings are suitable for the purpose.

40 45 At the left or rear end of the burner is located the atomizer 32 for viscous fuel. Within the atomizer, fuel from the supply pipe 19 is directed through a nozzle 33 into the mixing chamber 34 where it is met by a blast of steam from the steam pipe 22, and atomized thereby before passing through an orifice 35 leading to the fuel delivery tube 36.

45 50 55 Atomized fuel entering the fuel delivery tube 36 at 35, travels the full length of said tube and is discharged at the burner nose (Fig. 7). Surrounding the atomized fuel delivery tube 36 is a

fuel tube heater, which may be in the form of a jacket tube 37 spaced from the fuel delivery tube as shown, the passageway 38 thereby established being adapted to convey a heating medium, such as steam along substantially the full length of the fuel delivery tube. This fuel heating steam is to be discharged at the burner nose, in a manner to be described, and has as one of its functions the maintenance of a thoroughly atomized and highly combustible condition of the viscous fuel. The fuel heating steam is introduced to the jacket or passageway 38 by way of steam pipe 23, which feeds the steam into a chamber 39 of the atomizer housing. The housing forward wall 40 supports the rear end of jacket tube 37 by means of a threaded connection 41 at the packing gland 42. Gland 42 may be welded or otherwise fixed to the end of the jacket tube, as at 43.

The fuel delivery tube 36 may be maintained in concentric spaced relation to the jacket tube 37, 20 by threading it into a bore of an intermediate wall of the atomizer housing, as at 44. As will be evident, the steam chamber 39 is separated from the atomizing chamber 34 by said intermediate wall 45.

In a manner somewhat similar to that just described, a delivery tube 46 for oxygen or an equivalent gas for supporting combustion, is incorporated in the burner structure. The tube 46, threaded or otherwise fixed as at 47 within the 30 housing section 48, communicates with a chamber 49 to which oxygen or an equivalent combustion supporting gas is fed from a controlled source of supply by means of the pipe 21. A heater for the oxygen delivery tube may be in the form of a jacket tube 50 surrounding the tube 46 in spaced relation, providing a passageway or jacket 51 to be supplied with steam or other heating medium fed by way of pipe 28 to the steam chamber 52. It will be seen that the jacket 51 49 is placed in communication with the steam chamber 52, by supplying the jacket tube with a fixed bushing 53 which is externally threaded and engaged by threads 54 of a bore in the housing wall 55. This connection and the connection at 47 serve to maintain the tubes 46 and 50 in spaced concentricity. At the rear of housing section 48, a flange 56 provides a mounting means for the atomizer 32, which has a similar cooperative mounting flange 57.

Referring to Fig. 7, it will be noted that the oxygen delivery tube 46 and its jacket 50 extend substantially to the nose of the burner, in substantial parallelism with the fuel delivery tube 36 and its heating jacket 37. All of these elements are surrounded by an inner cooling jacket tube 58 of large diameter, extending substantially from the burner nose rearwardly to the housing 48. At its rear end, the inner cooling jacket tube may be supported in any suitable manner, for example as illustrated by Fig. 5, wherein the coupling ring 59 is shown provided with a bore 60 to receive the inner jacket tube 58, with provision made for a gasket or packing ring 61 to prevent leakage about the outer surface of the tube. The 55 gasket or packing may be held in compressed condition about tube 58 by means of a gland 62 threadedly engaging the threaded bore 63 of the coupling member as shown. An enlarged inner bore 64 of the gland forms a passageway whereby the entire open end 65 of the inner cooling jacket tube is placed in communication with a large chamber 66 of housing section 48, which is fed with gaseous fuel by the large pipe 20. This 60 gaseous fuel, as previously stated, may be coke 75

oven gas, illuminating gas, or a combustible gas of any other type. The flow of such gas preferably is controlled at the source, or at some location in the supply line exteriorly of the burner. Leakage of gas into the water jacket 31 and steam chamber 39 is precluded by the packings 61 and 42. A tight connection, of course, is perfected in any known manner, at the flanges 67 and 68 of the housing parts 59 and 48.

Gas from the chamber 66 may flow through the opening 64 and all about the tubes within the cooling jacket member 58, to finally emerge from the burner nose at the large spaces 69-69 of Fig. 8, where the gas mingles with the oxygen, the atomized fuel oil, and the steam from the heating jackets.

The gas tube 58, if supplied with a gas that carries particles of impurities, may require cleaning from time to time. Periodic or intermittent cleaning, or continuous cleaning if preferred, may be effected by incorporating in the burner a high pressure nozzle 72 for steam or other fluid, capable of dislodging such particles and blowing them out through the burner nose. The nozzle, as disclosed by Figs. 5 and 6, may be formed in the housing 48 as an arcuate narrow slot 72 in communication with a steam chamber 73 fed by the supply pipe 25. The nozzle slot preferably is located close to the open end 65 of the gas delivery tube, in position to dislodge any particles resting in the lowermost portion of the tube. Preferably, the arcuacy of the slot approximates that of the inside diameter of the gas tube, and may extend about the tube periphery 120 degrees, more or less, as clearly illustrated by Fig. 6. The inner wall 74 of the chamber 73 may be integral with the housing 48, and may be cut away or depressed slightly at 75 to accommodate the jacket tube 50 which is in close proximity to the nozzle slot at the depression.

From the foregoing, it will be understood that a blast of steam or other high pressure fluid directed into the chamber 73 by pipe 25, will strike and move, toward the forward end of the burner, any accumulation of particles that might be carried over by the gas and lodged in the gas delivery tube 58. Coke oven gas, for example, will often carry impurities that may lodge in the gas delivery tube, and by means of the nozzle arrangement herein disclosed, such impurities easily and quickly may be removed at intervals, by simply directing a high pressure fluid to the nozzle 72. The supply of high pressure fluid may be controlled by a two-way valve 72V interposed in steam pipe 22, by preference. The valve may be under the control of a burner attendant, or it may be opened periodically by automatic means if desired. The attendant may wish to clean the gas delivery tube by the aforesaid pressure method only when the burner is out of operation, and this procedure may be adequate under most conditions of usage. The accumulations leave the burner through the nose at 69.

The exterior of the burner comprises the long large tube 70, which extends from the flange 67 to the nose of the burner, and serves as the outer jacket member for cooling fluid. This tube 70 is commonly known as the burner barrel. The pipe 27 connects with the tube 70 near the burner nose, and supplies water as cooling fluid to the cooling jacket 31. A deflector or baffle 71 directs some of the coolant forwardly about the burner nose and certain structural parts there located, which are exposed to the destructive heat of the furnace. The coolant exhaust pipe

26 conveys coolant from the jacket 31 as rapidly as it enters by way of pipe 27.

The nose end of the burner will now be described with reference to Figs. 3, 4, 7 and 8 of the drawings. From Fig. 7, it will be noted that the forward end of the outer cooling jacket tube 10 carries a burner nose ring 16 applied thereto by means of a circumferential weld 17. The tip of the ring carries a part 18, which may be a machined weld of heat resistant metal or alloy, shaped as shown to provide a circumferential exterior groove 19 bounded by a rather sharp annular edge 20 extending radially outwardly. The groove and the sharp edge cooperate for precluding the accumulation of slag and other furnace impurities in such quantity as might close the burner nose. This tip construction will not be further detailed here, as it forms the subject of another patent already issued.

The ring 16 and part 18 are machined to provide an interior annular seat 21 adapted to receive snugly therein the forward edge of an enlarged cylindrical extension 22 of the gas delivery tube 58. The extension may be provided at one end with an internal flange 23, which may be welded or otherwise fixed to tube 58, as at 24. The opposite end of the extension carries a retaining means of any suitable type, herein disclosed as a slip ring 25 adapted to rest within an annular interior groove formed in the part 22, as shown. The ring 25 is adapted to retain the parts of the nose structure for assembly purposes.

Embraced within the cylindrical extension, or cage 22, is an assembly which properly may be referred to as a fluid-curtain generator, the function of which is to maintain over the open end of the burner nose a cone-shaped screen or curtain of steam or equivalent fluid. Such curtain or screen serves to prevent passage of furnace impurities or flying particles into the burner nose, and shields the open forward ends of tubes 36 and 46 from oxidation and carbonation in the presence of the generated and reflected heat within the furnace, thereby to avoid frequent cleaning and dressing of these and other parts of the burner nose.

The curtain generator comprises the parts illustrated by Figs. 3 and 4. In Fig. 3, the character 86 indicates generally the main body of the generator, which includes a cylindrical forepart or snout 87 having an enlarged annular flange 88. A diametral web 89, best illustrated by Fig. 8, extends partly within and partly outside the snout, and this web is enlarged at opposite sides of its middle to provide the hubs or bosses 90-91. The hubs or bosses are drilled or bored to receive and support the forward ends of jacket tubes 37 and 50 (Fig. 7). Other bores 92-93 receive and support, respectively, the forward ends of the viscous fuel delivery tube and the oxygen delivery tube. Thus, at the forward ends, the four tubes are supported by the main body part 86 of the fluid-curtain generator.

At the locations 94-94, the opposite ends of the web are provided with diametral bores which form radially disposed steam ports or passageways, opening to the exterior of the main body part 86. From the disclosure of Fig. 7, it will be seen that the ports 94 communicate with the steam jackets 38 and 51. To confine and direct the steam passing outwardly through the ports, an outer cylinder 95 (Fig. 4) is slipped over the forepart or snout 87 of the body 86. From Fig. 7 it is apparent that an annular seat 96 of the

outer cylinder receives the flange 88 of the main body part 87, thereby to establish an annular jacket or chamber 97 between the parts. The ports 94-94 communicate with this chamber, and direct into it the steam or heating fluid from the tube jackets 38-51.

As previously stated, a fluid-curtain is to be established ahead of the burner nose. The steam from the chamber 97 is utilized for this purpose. Referring to Fig. 7, it may be noted that the outer cylinder 95 of the fluid-curtain generator has an inwardly directed lip 98 which follows the periphery of the cylinder all the way around. The inner face of the lip, indicated at 99, is at an angle to the plane of the forward face of the lip, for the purpose of directing the steam from chamber 97 in a forward and inward direction toward the burner axis. It may be noted that the forward edge of snout 87 is chamfered, as at 100 (Fig. 3), so that the chamfer in conjunction with the inclined lip face 99, forms an annular nozzle capable of establishing a conical curtain of steam, the apex of which is formed forwardly of the burner nose substantially upon the axis of the curtain generator. The force of the steam issuing from the nozzle 99-100 is considerable, and its direction is such as to aid ejection of the various fuels from the burner while opposing entry of furnace impurities or particles into the burner nose from the front.

From the foregoing description, it is evident that the curtain generator assembly performs the several functions of supporting the several tubes 36, 37, 46 and 50, of collecting the steam from the heater jackets 38 and 51, and of delivering the jacket steam as a protective curtain or screen for the purposes above stated. The ports 94-94 are sufficient in size, or number, to freely relieve the heater jackets 38 and 51 of the steam or heating fluid issuing therefrom. While in the drawings the generator assembly is shown as being constructed of the two parts illustrated by Figs. 3 and 4, it may be desirable in practice to fabricate the part of Fig. 3 from a number of constituent pieces welded or otherwise joined together, to avoid complications in machining or molding. The number and nature of the parts constituting the complete element shown in Fig. 3, is a matter immaterial to the invention so far as performance is concerned, but from the standpoint of efficient shop practice, the web portion 89 may be initially built up from one or more pieces assembled and welded into the main body 86.

As indicated upon Figs. 7 and 8, the bores 92 and 93 which support the fuel tubes 36 and 46, respectively, may be milled out or otherwise cut away at 101 and 102, to provide a limited space about a portion of the circumference of each fuel tube, from which a limited amount of steam may escape about the fuel tube ends without passing through the annular nozzle 99-100. The auxiliary jets thereby provided constitute means to remove from the web 89 any drippings from the fuel tube 36 before the drippings can solidify, and in addition, the jets may serve as blow-out ports for any scale, dirt, or condensate that might otherwise tend to accumulate in the spaces 103 about the forward portions of the fuel tubes 36 and 46. Spaces 103 may be connected as at 107, if desired.

Fig. 2 illustrates a supporting member or spider 104 which may be employed at one or more locations within the length of the burner barrel, for precluding vibration and sagging of the jacket tubes 37 and 50. The spider may include several

radial legs 105, the outer ends of which rest against the inner surface of the gaseous fuel tube 50. The gas in traveling through the tube 58 toward the burner nose, flows freely all around the spider legs and the tubes supported thereby. The spider may be secured to the tubes by set screws 106 or any other form of fastening means.

Attention is directed to the fact that the atomizer illustrated at the left of Fig. 5 may atomize or condition for combustion, oil, tar, pitch or other viscous fuel introduced therein by way of the supply pipe 19, and discharged under pressure through nozzle 33 into the mixing chamber 34. Steam or other atomizing fluid under pressure enters the chamber by way of supply pipe 22, and acts upon the viscous fuel to atomize it prior to discharge through the port 35 and fuel delivery tube 36. The atomizing fluid pressure may be controlled at the source, or by placing a suitable control valve in the supply line 22, as will be understood. The nature or type of atomizer employed is a matter wholly immaterial to the present invention, as any known form of atomizer having the necessary capacity will suffice.

In the modified form of burner illustrated by Figs. 9 and 10, the jacketed tube for supplying oxygen or other combustion-supporting gas has been eliminated, but in all other respects the modified form carries all of the features of the burner hereinbefore described. The similarity is most clearly indicated by the application to Figs. 9 and 10, of the same reference characters applied to Figs. 7 and 8, with the digit "1" prefixed thereto. Accordingly, in Figs. 9 and 10, 136 and 137 are the atomized fuel delivery tube and its jacket, respectively, surrounded by the inner cooling jacket tube 158 which conveys gaseous fuel to the forward end of the burner. The space 138 between tubes 136 and 137 conveys steam or other heating fluid along the length of the fuel delivery tube, discharging same into the radial ports 194 and annular chamber 197, whence it emerges under pressure through the annular slit or nozzle 199-1100 to furnish the protective curtain or screen ahead of the burner nose as previously described.

The modified form of burner is to be supplied with atomized viscous fuel, gaseous fuel, and jacket steam, in substantially the manner explained in connection with Figs. 1 to 8, inclusive, and will of course include a high pressure cleaning nozzle for the gaseous fuel tube as indicated at 72 upon Figs. 5 and 6. In this instance, as well as in Fig. 1, the high pressure cleaning nozzle may receive its steam pressure from the supply pipe 22 as the two-way valve is manipulated at the will of the operator. It should be understood, however, that in either form of the device the nozzle pressure may be supplied otherwise.

Actual tests in open hearth furnaces have proven the superiority of the present burner over all others heretofore used or proposed. The improved burner of this invention has operated for greatly extended periods of time without need of cleaning, or shutting down for any reason. The flame produced was much hotter than usual, and it was found that the fuels leaving the burner nose were in a more favorable condition for combustion than could have been expected in any other known form of burner.

The self-cleaning features of the improved burner are highly advantageous, for obvious reasons; and the presence of the fluid-curtain or screen over the end of the burner nose con-

tributes greatly to the trouble-free performance of the burner. Whenever coke oven gas carrying particles of impurities is used in the burner, occasional use of the steam nozzle 72 will avoid clogging and the laborious cleaning operation which heretofore required taking the burner out of service. With the foregoing advantages and others hereinbefore mentioned, the tonnage of steel that can be produced in open hearth furnaces by means of the improved burner, is materially increased, with a substantial reduction in cost of manufacture.

It is to be understood that various modifications and changes in the structural details of the device may be made, within the scope of the appended claims, without departing from the spirit of the invention. The nature of the fuels used, and the heating and atomizing mediums employed, are subject to variation under justifiable circumstances.

What I claim is:

1. A burner of the class described, comprising in combination an inner elongate main tube having a cooling jacket, the inner tube being open at its forward and rearward ends, means for supplying gaseous fuel to the rearward end of said inner main tube for discharge from the forward end thereof, a viscous fuel delivery tube and a delivery tube for a combustion supporting gas, both extending lengthwise within the inner main tube, and each having a forward open end terminating near the forward end of the inner main tube, a pair of jacket tubes, one surrounding each of the delivery tubes in spaced relation, each jacket tube having an open forward end, means for supplying a heating fluid to the spaces defined by the jacket tubes, for maintaining an elevated temperature of the delivery tubes, and means for supplying viscous fuel and a combustion supporting gas to the respective delivery tubes for discharge from the forward open ends thereof.

2. A burner of the class described, comprising in combination, an inner elongated main tube having a cooling jacket, the inner tube being open at its forward and rearward ends, means for supplying gaseous fuel to the rearward end of said inner main tube for discharge from the forward end thereof, a viscous fuel delivery tube and a delivery tube for a combustion supporting gas, both extending lengthwise within the inner main tube, and each having a forward open end terminating near the forward end of the inner main tube, a pair of jacket tubes, one surrounding each of the delivery tubes in spaced relation, each jacket tube having an open forward end, means for supplying a heating fluid to the spaces defined by the jacket tubes, for maintaining an elevated temperature of the delivery tubes, means for supplying viscous fuel and a combustion supporting gas to the respective delivery tubes for discharge from the forward open ends thereof, and high pressure fluid means including a nozzle located near the open rearward end of the inner main tube, for blowing from said tube foreign matter deposited therein by the gaseous fuel.

3. A burner of the class described, comprising in combination, an inner elongate main tube having a cooling jacket, the inner tube being open at its forward and rearward ends, means for supplying gaseous fuel to the rearward end of said inner main tube for discharge from the forward end thereof, a viscous fuel delivery tube

and a delivery tube for a combustion supporting gas, both extending lengthwise within the inner main tube, and each having a forward open end terminating near the forward end of the inner main tube, a pair of jacket tubes, one surrounding each of the delivery tubes in spaced relation, each jacket tube having an open forward end, means for supplying a heating fluid to the spaces defined by the jacket tubes, for maintaining an elevated temperature of the delivery tubes, means for supplying viscous fuel and a combustion supporting gas to the respective delivery tubes for discharge from the forward open ends thereof, and means for collecting fluid emitted from the jacket tubes, and dispersing said fluid as a screen across the forward open end of the inner main tube, to deflect extraneous foreign matter tending to enter said main tube.

4. A burner of the class described, comprising in combination, an inner elongate main tube having a cooling jacket, the inner tube being open at its forward and rearward ends, means for supplying gaseous fuel to the rearward end of said inner main tube for discharge from the forward end thereof, a viscous fuel delivery tube and a delivery tube for a combustion supporting gas, both extending lengthwise within the inner main tube, and each having a forward open end terminating near the forward end of the inner main tube, a pair of jacket tubes, one surrounding each of the delivery tubes in spaced relation, each jacket tube having an open forward end, means for supplying a heating fluid to the spaces defined by the jacket tubes, for maintaining an elevated temperature of the delivery tubes, means for supplying viscous fuel and a combustion supporting gas to the respective delivery tubes for discharge from the forward open ends thereof, means for directing the heating fluid from the jackets as a protective screen across the forward open end of the inner main tube, and high pressure fluid means including a nozzle located near the open rearward end of the inner main tube, for blowing from said tube foreign matter deposited therein by the gaseous fuel.

5. A burner of the class described, comprising in combination, an inner elongate main tube having a cooling jacket, the inner tube being open at its forward and rearward ends, a viscous fuel tube and a tube for conveying a combustion supporting gas, both extending lengthwise within the inner main tube, and each having a forward end open and terminating near the forward end of the inner main tube, a jacket tube surrounding the viscous fuel tube in spaced relation, and open at its forward end, for conveying a heating fluid along the length of said fuel tube to maintain an elevated temperature of the latter, a second jacket tube similarly related to the tube for conveying combustion supporting gas, said second jacket tube having an open forward end terminating near the open forward end of the first mentioned jacket tube, means near the rear end of the burner for supplying viscous fuel to the viscous fuel tube, means for supplying a combustion supporting gas to the combustion supporting gas tube, means for supplying gaseous fuel of the interior of the inner main tube, and means for supplying a heating fluid under pressure to the spaces defined by the jacket tubes aforesaid, and means for directing the heating fluid issuing from said jacket tubes, to form a protective screen across the forward end of the inner tube of the burner.

6. A burner of the class described, comprising in combination, an elongate barrel having a forward nose end, tube means within the barrel for delivering combustible fuel to and through the nose end of the barrel, one of said tube means having connection with a source of combustible gas which may carry particles of impurities capable of accumulating in the gas tube, and high pressure fluid means including a nozzle having a mouth in the path of gas movement to blow out the particles of impurities from the gas tube in the general direction of the gas flow, said nozzle mouth being located under the gas tube and in a vertical plane passing through the center of the gas tube.

7. A burner of the class described, comprising in combination, an elongated barrel having a forward nose end, tube means within the barrel for delivering combustible fuel to and through the nose end of the barrel, one of said tube means having an open end within the barrel, said open end being in communication with a source of gaseous fuel to be discharged through said one tube means toward the nose end of the barrel, a controllable high pressure fluid means including a nozzle having an arcuate mouth for directing a fluid into the barrel, the mouth being disposed in close proximity to said open end, and substantially coinciding with a portion of the curvature of the inner wall of said open-ended tube, whereby a selected area of the tube interior is exposed to the scouring action of a high pressure fluid emitted by the arcuate mouth of the nozzle.

8. A burner of the class described, comprising in combination, an elongate barrel having a forward nose end, tube means within the barrel for discharging combustible material under pressure through the nose end of the barrel, heating jacket means about said tube means, adapted to convey a heating fluid along the tube means toward the nose end of the barrel, a fluid-screen generator disposed within the nose end of the barrel, including chamber means for collecting the heating fluid, and an annular nozzle in communication with said chamber means, said annular nozzle including a lip angularly inclined to direct a conical screen of fluid inwardly and forwardly of the barrel nose end, and through which screen the combustible material passes in leaving the nose end of the barrel.

9. A burner of the class described, comprising in combination, an elongate barrel having a forward nose end, tube means within the barrel for discharging combustible material under pressure through the nose end of the barrel, heating jacket means about said tube means, adapted to convey a heating fluid along the tube means toward the nose end of the barrel, a fluid-screen generator disposed within the nose end of the barrel, including chamber means for collecting the heating fluid, and an annular nozzle in communication with said chamber means, said annular nozzle including a lip angularly inclined to direct a conical screen of fluid inwardly and forwardly of the barrel nose end, and through which screen the combustible material passes in leaving the nose end of the barrel, and means for supporting said tube means in substantial parallelism with the barrel.

10. A burner of the class described, comprising in combination, an elongate barrel having a forward nose end, and means for discharging atomized fuel therefrom, tube means within the barrel for delivering oxygen under pressure through the nose end of the barrel, heating jacket means

about said tube means, adapted to convey a heating fluid along the tube means toward the nose end of the barrel, and nozzle means within said nose end of the barrel providing an annular chamber, said chamber having an interior port in communication with the heating jacket of the oxygen-delivering tube means, the nozzle means including an annular mouth in communication with the chamber, and a lip at the mouth angularly inclined to direct a conical stream of the heating fluid from said jacket inwardly and forwardly in advance of the barrel nose end.

11. A burner of the class described, comprising in combination, an inner elongate main tube open at its forward and rear ends, a multi-chambered housing secured relative to the tube in substantial alignment therewith at the rear end, one chamber of the housing being in communication with the open rear end of the tube, means supplying a gaseous fuel to said chamber for ejection through the main tube and its forward end, a viscous fuel delivery tube extending lengthwise through the main tube and through the gaseous fuel chamber, to a location exteriorly of the housing, said viscous fuel delivery tube having an open forward end terminating near the open forward end of the main tube, means supplying atomized viscous fuel to the opposite end of said delivery tube, a heating jacket tube surrounding substantially the full length of the fuel delivery tube and laterally spaced therefrom to provide a heating jacket, one end of the jacket tube being open at the forward end of the main tube, and the other end being open exteriorly of the housing, means supplying a heating fluid under pressure to said other end of the jacket tube, a nozzle formed in the housing and having communication with a second chamber of the housing, means supplying a high pressure fluid to said second chamber for feeding said nozzle, the nozzle being shaped arcuately in substantial conformity with the interior of the main tube, and limited as to the length of the arc, so as to direct the high pressure fluid into the rear open end of the main tube along a portion only of its inner surface.

12. A burner of the class described, comprising in combination, an inner elongate main tube open at its forward and rear ends, a multi-chambered housing secured relative to the tube in substantial alignment therewith at the rear end, one chamber of the housing being in communication with the open rear end of the tube, means supplying a gaseous fuel to said chamber for ejection through the main tube and its forward end, a viscous fuel delivery tube extending lengthwise through the main tube and through the gaseous fuel chamber, to a location exteriorly of the housing, said viscous fuel delivery tube having an open forward end terminating near the open forward end of the main tube, means supplying atomized viscous fuel to the opposite end of said delivery tube, a heating jacket tube surrounding substantially the full length of the fuel delivery tube and laterally spaced therefrom to provide a heating jacket, one end of the jacket tube being open at the forward end of the main tube, and the other end being open exteriorly of the housing, means supplying a heating fluid under pressure to said other end of the jacket tube, a nozzle formed in the housing and having communication with a second chamber of the housing, means supplying a high pressure fluid to said second chamber for feeding said nozzle, the nozzle being disposed in close proximity to the open end

of the main tube for directing a scouring stream lengthwise through the interior of the tube.

13. A burner of the class described, comprising in combination, an inner elongate main tube open at its forward and rear ends, a multi-chambered housing secured relative to the tube in substantial alignment therewith at the rear end, one chamber of the housing being in communication with the open rear end of the tube, means supplying a gaseous fuel to said chamber for ejection through the main tube and its forward end, a viscous fuel delivery tube extending lengthwise through the main tube and through the gaseous fuel chamber, to a location exteriorly of the housing, said viscous fuel delivery tube having an open forward end terminating near the open forward end of the main tube, means supplying atomized viscous fuel to the opposite end of said delivery tube, a heating jacket tube surrounding substantially the full length of the fuel delivery tube and laterally spaced therefrom to provide a heating jacket, one end of the jacket tube being open at the forward end of the main tube, and the other end being open exteriorly of the housing, means supplying a heating fluid under pressure to said other end of the jacket tube, a nozzle formed in the housing and having communication with a second chamber of the housing, means supplying a high pressure fluid to said second chamber for feeding said nozzle, the nozzle being disposed in close proximity to the open rear end of the main tube for directing a scouring stream lengthwise through the interior of the tube, and a fluid-curtain generator at the opposite forward end of the main tube, utilizing heating fluid discharged from the heating jacket for establishing a protective screen across the forward end of the main tube.

14. A burner of the class described, comprising in combination, an elongate barrel, a gaseous fuel delivery tube within the barrel, a delivery tube for atomized viscous fuel, and an oxygen tube, jacket tubes surrounding the oxygen and the viscous fuel delivery tubes, and means supplying heating steam under pressure to said jacket tubes, all of the tubes being in substantial parallelism and discharging in a common general direction forwardly of the burner.

15. A burner construction comprising in combination, an inner main tube to convey a fuel, and having a discharge end of substantial size, a cylindrical body substantially concentric with the discharge end of said tube, and having therein an annular chamber terminating in an annular narrow slot including means to direct a fluid from the chamber in coniform fashion forwardly of the discharge end of the inner main tube, a web spanning the cylindrical body and having a plurality of longitudinal and transverse communicating bores therein, the transverse bores meeting and communicating with the annular chamber of the body, a fuel tube and a combustion-supporting gas tube mounted in each longitudinal bore of the web, and heating jacket tubes surrounding the fuel tube and the combustion-supporting gas tube in spaced relation, the spaces provided by the heating jacket tubes being in fluid-communication with the transverse bores of the web, for conveying heating fluid under pressure to the annular narrow slot of the chamber.

16. A burner of the class described, comprising in combination, an elongate hollow barrel, a tube therein for conveying gaseous fuel, a delivery tube for atomized viscous fuel, and an oxidizing-fluid

delivery tube, said delivery tubes being spaced apart and disposed one above another within the tube for gaseous fuel, all of said tubes having corresponding open ends adjacent to one end of the elongate hollow barrel, fluid conducting means about each of said delivery tubes for maintaining a heated condition of said delivery tubes, and means near the open ends of said tubes for establishing a protective fluid curtain transversely thereof.

17. A burner of the class described, comprising in combination, an elongate hollow barrel, a tube therein for conveying gaseous fuel, a delivery tube for atomized viscous fuel, and an oxidizing-fluid delivery tube, said delivery tubes being spaced apart and disposed one above another within the tube for gaseous fuel, all of said tubes having corresponding open ends adjacent to one end of the elongate hollow barrel, fluid conducting means about each of said delivery tubes for maintaining a heated condition of said delivery tubes, and means near the open ends of said tubes for establishing a protective fluid curtain transversely thereof, utilizing that heating medium which heats the delivery tubes for viscous fuel and the oxidizing-fluid.

18. A burner of the class described, comprising in combination, an elongate hollow barrel, an inner jacket tube therein, a delivery tube for atomized viscous fuel, and an oxidizing-fluid delivery tube, said delivery tubes being spaced apart in substantial parallelism within the inner jacket tube of the barrel, and each having an open end exposed adjacent to one end of the barrel, a heating jacket member surrounding the oxidizing-fluid delivery tube in spaced relation, means for feeding a heating medium under pressure into the space between the oxidizing-fluid delivery tube and its surrounding jacket member, the direction of heating medium feed being toward the aforesaid open ends of the delivery tubes, with release of the heating medium occurring about the exposed open end of the oxidizing-fluid delivery tube.

19. A burner of the class described, comprising in combination, an elongate hollow barrel, an inner jacket tube therein, a delivery tube for atomized viscous fuel, and an oxidizing-fluid delivery tube, said delivery tubes being spaced apart in substantial parallelism within the inner jacket tube of the barrel, and each having an open end exposed adjacent to one end of the barrel, a heating jacket member surrounding the oxidizing-fluid delivery tube in spaced relation, means for feeding a heating medium under pressure into the space between the oxidizing-fluid delivery tube and its surrounding jacket member, the direction of heating medium feed being toward the aforesaid open ends of the delivery tubes, with release of the heating medium occurring about the exposed open end of the oxidizing-fluid delivery tube, and means deflecting the released heating medium as a protective screen transversely across the open end of said oxidizing-fluid delivery tube.

20. A burner of the class described, comprising in combination, an elongate hollow barrel, an inner jacket tube located inside the barrel and having rear and forward ends, a delivery tube for atomized viscous fuel extending lengthwise through the jacket tube and having an open forward end to deliver a combustible mixture forwardly of the burner, a viscous fuel atomizer near the rear end of the barrel, and supply pipes for viscous fuel and high pressure atomizing fluid

connected to said atomizer, means near the rear end of the inner jacket tube of the barrel for feeding gaseous fuel through said jacket tube, a high pressure cleaning nozzle located to direct a blast through the inner jacket tube from rear to front thereof, and means including a valve operative to selectively connect the high pressure fluid supply pipe to the nozzle or to the atomizer.

21. A burner of the class described, comprising in combination, an elongate hollow barrel having a forward open nose end, a delivery tube for atomized viscous fuel, and an oxidizing-medium delivery tube, said delivery tubes being spaced apart in substantial parallelism within the hollow interior of the burner barrel, and each having an open end exposed near the nose end of said barrel, separate heating jacket tubes surrounding said delivery tubes in spaced relation thereto and extending substantially the full length of their respective delivery tubes, means supplying atomized viscous fuel to the fuel delivery tube for discharge at the nose end of the barrel, means supplying an oxidizing medium to the oxidizing-medium delivery tube for discharge likewise at the nose end of the barrel, and means supplying a heating medium under pressure to the spaces between the delivery tubes and their respective jacket tubes, in a common direction toward the open forward ends of the delivery tubes.
22. A burner of the class described, comprising in combination, an elongate hollow barrel having a forward open nose end, a delivery tube for atomized viscous fuel, and an oxidizing-medium delivery tube, said delivery tubes being spaced apart in substantial parallelism within the hollow interior of the burner barrel, and each having an open end exposed near the nose end of said barrel, separate heating jacket tubes surrounding said delivery tubes in spaced relation thereto and extending substantially the full length of their respective delivery tubes, means supplying atomized viscous fuel to the fuel delivery tube for discharge at the nose end of the barrel, means supplying an oxidizing medium to the oxidizing-medium delivery tube for discharge likewise at the nose end of the barrel, and means supplying a heating medium under pressure to the spaces between the delivery tubes and their respective jacket tubes, in a common direction toward the open forward ends of the delivery tubes.
23. A burner of the class described, comprising in combination, an elongate hollow barrel having a forward open nose end, a delivery tube for atomized viscous fuel, and an oxidizing-medium delivery tube, said delivery tubes being spaced apart in substantial parallelism within the hollow interior of the burner barrel, and each having an open end exposed near the nose end of said barrel, separate heating jacket tubes surrounding said delivery tubes in spaced relation thereto and extending substantially the full length of the delivery tubes, means supplying atomized viscous fuel to the fuel delivery tube for discharge at the nose end of the barrel, means supplying an oxidizing medium to the oxidizing-medium delivery tube for discharge likewise at the nose end of the barrel, and means supplying a heating medium under pressure to the spaces between the delivery tubes and their respective jacket tubes, in a common direction toward the open forward ends of the delivery tubes, said spaces being open near the nose end of the barrel to release the heating medium in the general direction of fuel ejection.
24. A burner of the class described, comprising in combination, an elongate hollow barrel having a forward open nose end, a delivery tube for atomized viscous fuel, and an oxidizing-medium delivery tube, said delivery tubes being spaced apart in substantial parallelism within the hollow interior of the burner barrel, and each having an open end exposed near the nose end of said barrel, separate heating jacket tubes surrounding said delivery tubes in spaced relation thereto and extending substantially the full length of the delivery tubes, means supplying atomized viscous fuel to the fuel delivery tube for discharge at the nose end of the barrel, means supplying an oxidizing medium to the oxidizing-medium delivery tube for discharge likewise at the nose end of the barrel, and means supplying a heating medium under pressure to the spaces between the delivery tubes and their respective jacket tubes, in a common direction toward the open forward ends of the delivery tubes, said spaces being open near the nose end of the barrel to release the heating

medium in the general direction of fuel ejection, and means deflecting the released heating medium as a protective screen transversely of the nose end of the burner barrel.

24. A self-cleaning burner of the class described, comprising in combination, an elongate hollow barrel having a forward nose end, a delivery tube for atomized viscous fuel, and an oxidizing-medium delivery tube, said tubes being spaced apart in substantial parallelism one above 10 the other within the confines of the hollow barrel, and each having an open end exposed near the nose end of the barrel, a support member bored to receive snugly the open end portions of the delivery tubes, said bores being cut away outwardly along a limited portion of their circumference, at locations beneath the fuel delivery tube and above the oxidizing-medium delivery tube, to provide jets adjacent to the peripheral edges of the delivery tubes, and means supplying a high 15 pressure fluid to said jets, traveling therethrough

forwardly of the burner nose and adjacent to the peripheral edges of the delivery tubes, to perform a cutting action upon solids dripping from the forward end of the fuel delivery tube.

JAMES WILLIAM PENNINGTON.
